To all whom it may concern:

Be it known that we, Walter F. Piper, a citizen of the United States, residing at Chicago, in the county of Cook and State of Illinois, and Joseph J. Soldat, a citizen of the United States, residing at Chicago, in the county of Cook and State of Illinois, have invented a new, original, and ornamental Design for a Wheelbarrow, of which the following is a specification, reference being had to the accompanying drawings, forming a part thereof.

In the drawings:

Figure 1 is a perspective view of a wheelbarrow, embodying our new design;

Figure 2 is a top plan view;

Figure 3 is a side elevational view;

Figure 4 is a front elevational view; and

Figure 5 is a rear elevational view.

We claim:

The ornamental design for a wheelbarrow, substantially as shown.

WALTER F. PIPER.
JOSEPH J. SOLDAT.
